US00D960149S

(12) **United States Design Patent** (10) **Patent No.:** **US D960,149 S**
Eguchi et al. (45) **Date of Patent:** **** Aug. 9, 2022**

(54) **COMPUTING DEVICE**

(71) Applicant: **Microsoft Corporation**, Redmond, WA (US)

(72) Inventors: **Shunjiro Eguchi**, Sammamish, WA (US); **Hua Wang**, Sammamish, WA (US); **Richard Dean Harley**, Sammamish, WA (US)

(73) Assignee: **Microsoft Corporation**, Redmond, WA (US)

(**) Term: **15 Years**

(21) Appl. No.: **29/707,898**

(22) Filed: **Oct. 1, 2019**

(51) LOC (13) Cl. **14-02**

(52) U.S. Cl.

USPC **D14/327**

(57) **CLAIM**

The ornamental design for a computing device, as shown and described.

DESCRIPTION

FIG. 1 is a perspective view of a computing device showing our new design in a closed configuration;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the computing device of FIGS. 1-7 shown in an open configuration;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The broken lines depicting the remainder of the computing device in FIGS. 1-5 and in FIGS. 7-14 show features that form no part of the claimed design.

1 Claim, 14 Drawing Sheets
